UNITED STATES PATENT OFFICE.

THEODORE W. FOSTER, OF PROVIDENCE, RHODE ISLAND.

DESIGN FOR A BOX.

SPECIFICATION forming part of Design No. 28,685, dated May 24, 1898.

Application filed April 13, 1898. Serial No. 677,501. Term of patent 3½ years.

To all whom it may concern:

Be it known that I, THEODORE W. FOSTER, of Providence, in the county of Providence and State of Rhode Island, have invented and 5 produced a new and original Design for Boxes for Manicure and Similar Articles, of which the following is a specification, reference being had to the accompanying drawings, forming part thereof.

10 Figure 1 is a top view of a box or case for a set of manicure or similar articles, showing my design. Fig. 2 is an end view of the same.

The leading and material feature of my design consists in the curved front and rounded 15 back of an oblong box provided with an ornamental latch on the curved front, as will be more fully set forth hereinafter.

In the drawings, 3 indicates the end of and 4 the curved front of the lower part, and 3' the 20 end of and 4' the curved front of the upper

part, of the box or case. The upper part of the box is rounded at 7, which rounded surface extends from end to end of the box and starts for the point 7', extending, approximately, to the hinge-line of the division of the 25 box. 5 is the latch.

The box presents to the eye the pleasing appearance of a swell-front box or case having a rounded back.

Having thus described my invention, what 30 I claim as new, and desire to secure by Letters Patent, is—

The design for a box for manicure or similar articles herein shown and described.

In witness whereof I have hereunto set my 35 hand.

THEODORE W. FOSTER.
